BY HIS ATTORNEY,

Frank S. Allen

UNITED STATES PATENT OFFICE.

ALLISON N. CLARK, OF PLAINVILLE, CONNECTICUT.

DESIGN FOR A MANICURE-BLADE.

SPECIFICATION forming part of Design No. 35,746, dated February 18, 1902.

Application filed January 7, 1902. Serial No. 88,803. Term of patent 14 years.

To all whom it may concern:

Be it known that I, ALLISON N. CLARK, a citizen of the United States, residing at Plainville, Hartford county, State of Connecticut, have invented and produced a new and original Design for Manicure-Blades, of which the following is a specification, reference being had to the accompanying drawings, forming part thereof.

10 Figure 1 is a plan view of a manicure-blade, showing my new design. Fig. 2 is an edge view of the same, and Fig. 3 is a cross-sectional view taken on the line 3 3 of Fig. 1.

The essential features of my design consist 15 of a blade with substantially parallel edges and formed as an elongated oval in cross-section, each of the opposite faces of said blade being formed with a central longitudinal depression or groove *a*, the bottoms of which 20 grooves present a knurled appearance. One

end of the said blade is tapered convexly, as at *b*, to a point *b'*, and the opposite end of said blade is tapered concavely, as at *c*, and terminates in an extension *d*, having parallel sides and whose end wall *d'* is diagonal to the 25 said parallel sides. The said extension *d* is formed with a circular opening *e*, that is parallel with the longest diameter of the body of the said blade.

Having described my invention, what I 30 claim as new, and desire to secure by Letters Patent, is—

The design for a manicure-blade as herein shown and described.

Signed at Plainville, Connecticut, this 19th 35 day of December, 1901.

ALLISON N. CLARK.
